Peter W. Mosher

BY *Peter W. Mosher* ATTORNEY

UNITED STATES PATENT OFFICE.

PETER W. MOSHER, OF STOCKTON, CALIFORNIA.

TRAIN-CONTROL SYSTEM.

Application filed April 29, 1925. Serial No. 26,690.

This invention relates to improvements in railway equipment and especially to automatic electric brake setting systems of the normally open circuit type in which the engine circuits are closed to apply the brakes when two engines approach each other within a certain distance or are in the same block.

The present invention makes use of practically the same engine circuit and brake controlling means as shown in my Patent No. 1,539,500 dated May 26th, 1925, and is especially intended for individual installation on each track of a double-track road, on which the traffic only moves in one direction.

The principal object of this invention is to arrange a track circuit which controls the closing of the engine circuit, and interpose connections between the block signal semaphores and said track circuit, in such a manner that the brakes on an engine entering the block in which the semaphore is set against the train, will be automatically set regardless of any train ahead.

At the same time the brakes are not applied on a head train, permitting the latter if still in the block to continue on its way so that it may get out of said block as soon as possible.

Another object is to arrange the system in such a manner that in the event that the head train fails to set the semaphore the presence of such train in the block will cause a brake application to be made on any train entering the block past the inoperative semaphore.

Therefore with my improved system, while the automatically actuated block signal semaphores, as at present used, will cause an automatic stopping of a train to be effected, if the train passes a semaphore set against it, at the same time the failure of the semaphore to function will not affect the operation of my system if another train is in the block ahead of the semaphore. Of course if the semaphore is down and there is no train in the block ahead the brakes on a following train will naturally not be set, since the track is clear.

These objects I accomplish by means of such structure and relative arrangement of parts as will fully appear by a perusal of the following specification and claims.

In the drawings similar characters of ref-

erence indicate corresponding parts in the several views:

Fig. 1 is a diagrammatic plan of my improved system shown on a one-way track with two adjacent semaphores of a block system and indicating two trains, one between the semaphores and the other just entering the block; the rear semaphore having been set by the head train.

Fig. 2 is a similar view with the two trains in the same position, but showing the rear semaphore as having failed to function when the head train passed thereby.

Referring now more particularly to the characters of reference on the drawings, the numerals 1 and 2 denote the rails of each track insulated from each other but continuous between adjacent semaphores S and S', at which points they are also insulated from the corresponding rails therebeyond at both ends.

Adjacent the semaphores are third rail lengths 3, insulated from the main rails and from each other. Each third rail also has an insulation break in the same in transverse alignment with the main rail breaks. At each semaphore is located a pair of spaced wires 4 and 5. The wire 4 is connected to the adjacent rail 3 on one side of the insulation break and to the rail 2 on the other side of the break. The wire 5 is connected to the rail 3 on the other side of the break and to the rail 2 on the opposite side of its break relative to the connection of said wire with the rail 3. This is plainly shown in the drawings.

Each semaphore arm 6 is connected to a switch or contact member 7 arranged, when the semaphore is set or raised to a horizontal position, to bridge across the wires 4 and 5; and when the semaphore arm is down, to be clear of said wires as clearly shown.

Wires 8 extend from the rail sections 1 preferably centrally of their length between the semaphores, to a common continuous wire 9 supported from the usual pole line found along railroad tracks.

The foregoing forms the standing or track circuit arrangement usable in connection with an engine circuit as shown in the above mentioned patent. In the present application I only show the main features of such engine circuit, since the additional features

do not affect the operation of the present system.

I have here indicated two engines A and B travelling in the same direction or from left to right on the drawing.

Each engine has lead wheels 10 and a shoe or contact 11 adapted to engage the third rail 3 and insulated from the wheels and the remainder of the engine. A wire 12 is connected at one end to the wheels 10 and at the other end to a battery 13 carried by the engine with a hand switch 14 normally held closed by a weight interposed therein.

A wire 15 from the shoe 11 extends to one terminal of a solenoid 16, the other terminal of which is connected to the battery. The circuit therefore is normally broken since the shoe 11 is insulated from the wheels 10.

The core 17 of the solenoid is connected to an arm 18 which in turn is connected to the operating handle or lever 20 of the air brake valve 21. When the handle is in the off position the core 17 is practically clear of the solenoid. I have here shown the rear engine B as just about to enter the block and with the shoe 11 on the rail 3, while the head engine A is in the block with its shoe 11 clear of any rail 3.

In Fig. 1 it is assumed that the engine A has set the semaphore S when passing by the same. This is done as now by the front wheel of the engine passing over the adjacent main rail break and causing the semaphore actuating circuit to be broken, an operation which raises the semaphore and with my improved system causes a connection to be made between the wires 4 and 5.

In order to insure that the brakes will not then be applied to the engine setting the semaphore the length of the rail 3 beyond the insulation break in the direction of movement of the engine, is shorter than the distance from the front wheels 10 to the shoe 11, which is at the extreme front end of the engine. This will cause said shoe to be clear of the rail 3 by the time the wheels cause the main rail break to set the semaphore.

In operation with the engines in position as shown in Fig. 1, the engine A is not affected by the engine B and is free to continue on its way. The engine B, however, entering the block at the semaphore S, which is set, will instantly have a brake application made thereon.

This is because the circuit is then closed from the battery 13 through the wire 12 to the wheels 10, through rail 2 and wire 5, across member 7 and through lead 4 to rail 3, thence to shoe 11 and through wire 15 and solenoid 16 to the battery. The solenoid will then be energized causing the arm 18 to pull the handle 20 around to a brake setting position.

As soon as the shoe 11 clears the rail 3 the circuit will be broken, but the solenoid core

will not move out of the solenoid itself, and the handle 20 tends of course to remain in whatever position it has been placed. The brakes will therefore be kept applied until the train comes to a stop or until the engineer releases the same, the handle 20 having a sufficient length beyond the connection of the arm 18 therewith to serve as a hand grip.

The weighted switch 14 is for the purpose of enabling the circuit to be held open by the engineer as the train passes a set semaphore in the event that the engineer has seen the signal and has the train already under control. The weight insures that the switch will be at once closed as soon as the engineer releases his hold on the same.

In Fig. 2 the rear semaphore S is shown as being down or indicating a clear track, even though the engine A is ahead of the same and still in the block, the assumption being that the semaphore has failed to operate when the engine passed by the same.

In this case no connection is made between the wires 4 and 5 but the brakes on the rear engine B will be applied just the same as soon as the shoe 11 on said engine engages the rail 3 by reason of the engine A being still in the block.

This is because the circuit is now closed from the battery 13 through the wire 12 to the wheels 10, along rail 1, through the adjacent wire 8 to and along the lead 9, to and along the lead 8 ahead to the rail 1 beyond the insulation break, across the wheels 10 of the engine A to the rail 2, along rail 2 to lead 4, along wire 4 to rail 3, along rail 3 to shoe 11, and from said shoe to and through the solenoid 16 and battery by means of wire 15. Under these conditions also the engine A ahead will not be affected and can travel on and out of the block without interruption.

Various mechanisms have been devised for operating semaphores, those now employed being usually of the closed circuit type. I have here shown a diagrammatic operating means for semaphore S, it being understood that each semaphore has its own individual operating mechanism. As here shown, the arm 6 is connected to a counter-weight arm 22 which tends to raise the arm 6. A solenoid 23 whose core 24 is attached to the arm 22, acts when energized to hold the arm 6 lowered.

One terminal of the solenoid is wired to one rail, and the other terminal to the other rail. A track battery 25 is also wired to the rails, on the same side of the insulated break therein as the connections of the solenoid therewith. The circuit through the solenoid is therefore normally closed, maintaining the arm lowered. When however a train bridges the rails, a short circuit is formed, causing the solenoid to be deenergized, whereupon the weight is free to act on and raise the arm 6.

The solenoid will remain deenergized as long as the train remains on an unbroken section of track, but upon the passing of the train from such section, the circuit to the 5 solenoid is reestablished, and the arm 6 is drawn to its lowered position.

From the foregoing description it will be readily seen that I have produced such a device as substantially fulfills the objects of 10 the invention as set forth herein.

While this specification sets forth in detail the present and preferred construction of the device, still in practice such deviations from such detail may be resorted to 15 as do not form a departure from the spirit of the invention, as defined by the appended claims.

Having thus described my invention what I claim as new and useful and desire to secure by Letters Patent is:

1. An automatic brake setting system for railway vehicles including with a normally open electric brake actuating circuit on each vehicle, a block-signal system having spaced 25 semaphore arms each arranged to be raised in turn by a vehicle on the track passing the arms; means controlled by the raising of a semaphore by a passing vehicle for causing the closing of the brake actuating circuit to 30 be effected on a subsequent vehicle when the latter reaches said raised semaphore, and means whereby if the semaphore fails to be raised by the first vehicle the brake circuit on a subsequent vehicle reaching said semaphore will still be closed as long as said 35 first vehicle is within a predetermined distance ahead of said subsequent vehicle.

2. An automatic brake setting system for railway vehicles including with a normally 40 open electric brake actuating circuit on each vehicle, a block-signal system having spaced semaphore arms each arranged to be raised in turn by a vehicle on the track passing the arms; means controlled by the raising of a 45 semaphore by a passing vehicle for causing the closing of the brake actuating circuit to

be effected on a subsequent vehicle when the latter reaches said raised semaphore, and means controlled by the presence of a vehicle 50 in the block ahead of a semaphore for causing the brake circuit on a vehicle subsequently reaching said semaphore to be closed if said first named vehicle has failed to raise the semaphore.

3. An automatic brake setting system for 55 railway vehicles including with a normally open electric brake actuating circuit on each vehicle, a block-signal system having spaced semaphore arms each arranged to be raised in turn by a vehicle on the track passing the 60 arms; means controlled by the raising of a semaphore by a passing vehicle for causing the closing of the brake actuating circuit to be effected on a subsequent vehicle when the latter reaches said raised semaphore, and circuit means independent of the semaphores 65 and controlled by the presence of a vehicle in the block ahead of a semaphore for causing the brake circuit on a vehicle subsequently reaching said semaphore to be closed 70 without affecting the circuit on the first named vehicle.

4. An automatic brake setting system for 75 railway vehicles including with a normally open electric brake actuating circuit on each vehicle, a block-signal system having spaced 80 semaphore arms each arranged to be raised in turn by a vehicle on the track passing the arms; means controlled by the raising of a 85 semaphore by a passing vehicle for causing the closing of the brake actuating circuit to be effected on a subsequent vehicle when the latter reaches said raised semaphore, and circuit means independent of the semaphores 90 and controlled by the presence of a vehicle in the block ahead of a semaphore for causing the brake circuit on a vehicle subsequently reaching said semaphore to be closed regardless of the position of the semaphore already passed by the first named vehicle.

In testimony whereof I affix my signature.
PETER W. MOSHER.
